SAFETY PUSH BUTTON KNIFE

Edward J. Conklin, Bridgeport, Conn.

Application May 18, 1938, Serial No. 208,515

10 Claims. (Cl. 30—159)

This invention relates to pocket knives of the safety push button type, and has for an object to provide a simple and effective means of locking the blade either in the closed or open position, and in which it will be difficult to inadvertently release the locking means, and thus provide a real safety push button knife.

It is also an object to provide such a safety feature which in normal operation will be automatically held in and returned to the locking position with ordinary movements from this position, but may be moved to the full released position and remain there for easy and convenient use of the knife.

15 It is another object of the invention to provide these safety features without adding extra parts to the constructions of push button knives now commonly used, and thus effect the safety features without increasing the cost of manufacture.

With the foregoing and other objects in view I have devised an improved construction several embodiments of which are illustrated in the accompanying drawing forming a part of this specification, it being understood that various changes and modifications may be employed within the scope of the invention.

In this drawing:

Fig. 1 is a plan view of one end portion of a 30 push button knife embodying my improved construction with the cheek plate removed;

Fig. 2 is a longitudinal section thereof substantially on line 2—2 of Fig. 1 but showing the cheek plate in position;

35 Fig. 3 is a top plan view of Fig. 2;

Fig. 4 is a transverse section substantially on line 4—4 of Fig. 2;

Figs. 5 and 6 are a top plan view and side elevation respectively of the safety slide;

40 Figs. 6a and 6b are a top and side view respectively of one end portion of the lock spring;

Fig. 7 is a plan view of one end of the lining plate;

Fig. 8 is a side elevation thereof showing a 45 safety slide thereon in the released position;

Fig. 9 is a view similar to Fig. 1 of the so-called safety push button dagger showing a modified construction;

50 Fig. 10 is a longitudinal section substantially on line 10—10 of Fig. 9;

Fig. 11 is a transverse section substantially on line 11—11 of Fig. 10;

Fig. 12 is a plan view of one end of the lining plate of the construction of Figs. 9 and 10;

Fig. 13 is a side elevation thereof showing a safety slide in the released position;

Figs. 14 and 15 are plan and side views respectively of the safety slide used in the construction of Figs. 9 to 13;

5 Fig. 16 is a view similar to Figs. 1 and 9 of a larger type of knife showing another modified construction;

Fig. 17 is a longitudinal section thereof substantially on line 17—17 of Fig. 16;

10 Figs. 18 and 19 are a top plan and side view respectively of the safety slide used in the construction of Figs. 16 and 17; and

Figs. 20 and 21 are a top plan and side view respectively of a portion of the liner plate of the 15 construction of Figs. 16 and 17.

Referring first to the type of device shown in Figs. 1 to 8 inclusive, the knife comprises the usual construction of a push button knife, the push button control being shown for one blade only. 20 It comprises the usual metal lining plates 1 and 2 between which the blade 3 is pivoted in the usual manner on a transverse rivet or pin 4 passing through the lining plates and the cheek plates 5 and 6. The pivot pin 4 may have a tubular bushing 7 on which the blade has its bearing, and this sleeve may be turned or flanged over at its opposite ends on the lining plates to assist in holding them in position. In Fig. 1 the upper cheek plate 5 is removed showing the operating 30 mechanism in plan view. Mounted in a space between the linings 1 and 2 is a spring 8 secured in any suitable manner, such for example as being inserted between one of the transverse securing rivets 9 and the spacer back member 10 35 mounted between the linings 1 and 2 to retain them in proper spaced relation and also having the usual shoulder 11 at one end to engage a shoulder 12 on the blade to limit the opening movement of the blade. It will be understood 40 when the blade is released or unlocked this spring 8 throws it outwardly about its pivot 4 to the open position.

The blade is locked in either the closed or opened position by means of a locking lever 13 45 operated to release the blade by means of a push button 14 on the lever extending through an opening in the cheek plate 5 to a position where it may be easily pushed inwardly by a thumb or finger to operate this lever to unlock 50 or release the blade. The blade is locked in the closed position by the opposite end 15 of the lever seating in a recess 16 in the top wall of the blade, and the blade is locked in the open position by this end of the lever 13 seating in 55

a recess 17 located at the opposite side of the pivot 4 from the recess 16. The locking lever 13 is mounted on a pivot pin 18 held at opposite sides of the lever in ears 19 cut and rolled up 5 from the liner 1. A flat spring 20 is mounted on the upper surface of the liner 1 and in a recess 5a in the inner wall of the cheek plate 5 by inserting one end thereof under a lug 21 lanced and struck up from the lining 1. The opposite 10 end of this spring indicated at 21 extends under the end of the lever 13 or push button 14 and tends to lift this end of the lever and thus to retain the locking end 15 of the lever against the blade and seat it in one of the notches 16 or 17 when in alignment therewith. The locking 15 or safety slide 22 is mounted on the top of the lining 1 and has a lower spring arm 23 sliding on the top of this lining at one side of the spring 20. The top portion of this slide 22 is wider than the arm 23 as indicated at 24 so as to overhang the spring 20, and carries the finger piece 25 which projects through an elongated slot 26 in the cheek plate 5 in a position where it may be easily operated to shift the slide 22 to and 20 from the locking position. At one end where the spring arm 23 is joined to the top 24 these members are pinched together, as indicated at 27, so that it may be slid under the laterally extending end portion 21 of the spring 20 as shown 25 in Figs. 1 and 2, so as to prevent depression of this end of the spring and therefore prevent depression of the button 14 and operation of the lever 13 to unlock the blade. It will be understood when this slide 22 is shifted to the right 30 as viewed in Figs. 1, 2 and 3 the end 27 will be shifted from under the end 21 of the spring and permit operation of the button 14 by pressing inwardly on this button to raise the opposite end of the lever 13 for the notch in the blade 35 to unlock or release the blade. If the blade is in the closed position when this button is depressed the blade will be thrown to the open position by the spring 8, and the blade will be locked in the open position by the end 15 of the lever 13 seating in the notch 17 in the blade. 40

This construction so far described is old and has been used in pocket knives, but it has a serious objection in that the friction of the spring arm 23 on the lining and the top portion 45 24 on the cheek is not sufficient to prevent accidental shifting of the safety slide, either inadvertently while handling the knife, or by rubbing of other articles in the pocket on the finger piece 25, or by rubbing of the material of the pocket itself on this member, so as to shift the safety slide to the released position, and then pressure on the button 14 in the pocket may release the blade so that it will be thrown to the half open position with the danger of serious injury to one carrying the knife or the liability of 50 severely cutting the hand should it be inserted in the pocket with the knife in this condition.

I have overcome this objection by providing on the lining 1 in alignment with the free end 55 of the spring arm 23 an inclined tongue 28. This tongue may be conveniently formed by lancing the lining and bending the tongue upwardly. The front wall 29 of this tongue is inclined at a proper angle and is in alignment with the free end of the spring arm 23 so that if the slide 22 is shifted 60 to the right or toward the released position the free end of this arm 23 will ride up on the incline 29. It will be seen that because of the spring action or resiliency of the arm 23 the pressure 65 of its free end on the inclined surface 29

will by a camming action on this surface tend to shift the slide 22 to the left or to the locked position with its end 27 under the end 21 of the spring 20 to thus retain the button 14 and lever 13 in locked position. Thus any pressure 5 on the finger piece 25 in ordinary handling, or when the knife is carried in the pocket, tending to shift the slide 22 to the right or the released position will be resisted by this camming action, and even if the pressure is sufficient to 10 shift the safety slide somewhat, as soon as this pressure on the finger piece 25 is released this camming action will immediately and automatically shift the safety slide back to its locking position. It will be seen that unless some means 15 is provided for holding the safety slide in the fully off or released position the safety feature would be fully automatic, and on any movement of the slide from the locking position it would be immediately returned to the locking position 20 as soon as pressure causing this movement was released. This would mean that when using the knife the operator would be required to hold the safety slide in the released position while depressing the button 14 to unlock the blade. This would 25 be rather inconvenient and therefore the parts are so arranged and proportioned that when the safety slide 22 is shifted to the extreme right hand or released position the free end of the spring arm 23 will ride up on to the top of the 30 tongue 28 as shown in dotted lines Fig. 2 and full lines Fig. 8. It will be seen this removes the arm 23 from the inclined surface 29 and therefore there is no camming action tending to shift the safety slide back to the locking position. 35 It will therefore remain in this position for free operation of releasing button 14 until the slide is shifted from this position. A lug or ear 20a (Figs. 1, 2, 6a and 6b) may be cut and bent up from the spring 20 in alignment with 40 the end of the arm 23 to be engaged by the end of this arm and thus form a stop to limit the amount the arm will ride onto the tongue 29.

The parts are so constructed and arranged however that a slight movement of the safety 45 slide to the left or toward the locking position will carry it off the top of the tongue 28, and then cam action on the inclined wall 29 thereof will immediately shift the safety slide to the locking position. This can be made as sensitive 50 as desired by positioning the end of the lug 20a to permit the arm 23 to ride the proper amount onto tongue 29, and it is preferably made so that a slight pressure on or movement of the finger piece 25 will shift it sufficiently to bring 55 the automatic camming action into operation. This will be secured by positioning lug 20a to permit arm 23 to ride only a short distance onto tongue 29. Thus even though the knife may be placed in the pocket with the safety slide in the released position rubbing action of other articles 60 in the pocket or pressure of the material of the pocket itself will soon shift the slide sufficiently so that this camming action will automatically shift the slide to the fully locked position. Then as above described ordinary pressures tending to move it in the opposite direction will automatically be overcome by the camming action. Thus 65 it will be seen this tongue 28 and arm 23 control the retracting motion of the safety slide 22 so that this slide is held in the locked position until deliberately unlocked, and any inadvertent pressure on the operating member 25 insufficient to shift the slide to the fully unlocked position will be counteracted and the slide immediately shifted 70 75

back to the fully locked position as soon as this pressure is removed. This will make a semi-automatic safety push button knife, but it will be seen as pointed out above that if it is not constructed so that the slide will ride over the top of the tongue 28 it will be fully automatic. However, the semi-automatic arrangement is preferred as it is easier and more convenient to operate.

10 The same principle is employed in the modified constructions of Figs. 9 to 21. In the construction of Figs. 9 to 15 used in the so-called "dagger" type the locking means for the blade 30 is somewhat different than that for the smaller 15 type of knife shown in Figs. 1 to 8. The blade is pivoted on the bushing 7 around the transverse rivet or pin 31 in the usual manner and the blade is between the linings 32 and 33. The locking lever 34, instead of being pivoted on a 20 transverse pin in rolled up ears as in the first form, is provided with a transverse notch or groove 35 on its lower side seated on a transverse integral bar 36 left in the lining 32 when the 25 openings 37 and 38 are punched therein. The free end of the lever passes through the opening 38 to seat in the notches 39 and 40 in the blade to lock the blade in either the closed or opened 30 position. The lever 34 carries the push button 41 projecting through an opening in the cheek 35 42 for operation by the thumb or finger as in the first form. In this construction the safety slide 43 is of resilient spring metal comprising an upper portion 44 carrying the finger piece 45 which projects through an elongated opening 46 in the cheek 42. The slide 43 is reduced in width and bent upon itself as shown at 47 to provide a spring arm 48 extending under the top portion 44. Mounted on the top of the lining 32 is a flat spring 49 which has an elongated 40 central opening 50 extending for the greater portion of the length of this spring. It is mounted on the lining 32 by inserting the closed portion of this spring at the right hand end of this slot under a tongue 51 cut and raised up from the lining 32. The opposite closed end 52 of the spring rests on top of the locking lever 34 beyond the pivot 36 so as to depress this free end of the lever into the notches in the blade to lock the blade in different positions. The safety slide 55 43 is mounted with the spring arm 48 within the longitudinal slot 50 in the spring 40 and bearing on top of the lining 32 with the finger piece 45 projecting through the slot 46 in the cheek 42, and when this slide is in the locking position as shown in full lines Fig. 10 the end portion 47, which is inclined downwardly somewhat, extends under the button 41 and the end of the locking lever 34 to prevent depression of the button and to hold the lever in the locking 60 position.

To secure the automatic camming action the connection of the tongue 51 to the lining 32 is inclined as shown at 53 corresponding to the incline 29 of the first form. This incline is in alignment with the free end of the spring arm 48, so that as the safety slide 43 is shifted to the right the free end of this arm 48 rides up on this inclined wall 53 and by the camming action caused by the resiliency of the spring tends to shift the safety slide 43 to the left or to the locked position with its end portion 47 extending under the button 41 and the free end of the lever on which it is mounted. This action is also assisted by the downward inclination of the 70 end portion 47 of the slide. It will be seen this

forms an inclined wall 54 on the underside of this end portion, and as this end portion projects over the edge of the opening 47 into this opening as shown in Fig. 10 it will be seen that movement of the slide 43 to the right will cause a camming action of this inclined wall 54 on the end 55 of the opening 37, which because the resiliency of the slide 43 presses the top portion 44 thereof against the under surface of the cheek 42 tends to shift the slide 43 to the left and retain it in the locked position.

In order to retain this safety slide in the unlocked position the tongue 51 is provided with a short flat surface 56 at the upper portion of the incline 53 on to which the free end of the 15 arm 48 may slide and rest when the slide 43 is shifted to the right as shown in Fig. 13. This movement to the right may be limited by the free end of the arm 48 engaging a shoulder 57 at the inner end of the flat portion 56. The 20 operation of this device is the same as that described in connection with the form of Figs. 1 to 8. When the blade is unlocked by depressing the button 41 the spring 30a throws the blade to the open position the same as spring 8 in 25 the first form.

The construction of Figs. 16 to 21 also operates in the same manner although the parts are constructed and arranged somewhat differently. This construction is usually used with a larger or 30 heavier type of knife. The construction and mounting of the locking lever for the knife blade is the same as that used in Figs. 9 and 10 and therefore the same reference numerals are used 35 for these parts as are used in Figs. 9 and 10. In this construction, however, the mounting tongue 59 for the spring 60 for holding the locking lever 34 in locking position is cut from the lining 61 leaving it attached at one edge, and then it is bent upwardly about this edge to the position 40 shown. The rearward free edge of this tongue is inclined as shown at 62 to form the inclined camming wall corresponding to the inclined walls 29 and 53 of the first two forms. The spring 68 has a longitudinal central slot 63 and the closed 45 right hand end portion of the spring is inserted under the hook 64 formed by the tongue 59. The other enclosed end portion 65 rests on top of the lever 34 to the left of the pivot 36 and thus tends to hold the lever in the locking position.

The safety slide 66 is a piece of spring metal bent to substantially U shape as shown in Figs. 18 and 19. The upper portion 67 is reduced in width at the left hand end to form the loop connection 68 and the lower spring arm 69. The top 55 67 carries the operating finger piece 70. In mounting this slide the arm 69 rests on top of the lining 61. Within the slot 63 of the spring 60 in the normal locking position shown in full lines Figs. 16 and 17 the looped end 68 lies under 60 the button 41 and retains the lever 34 in the locking position. The inclined surface 62 is in alignment with the end of the spring arm 69 so that when the slide 66 is shifted to the right this arm rides up on the incline 62 and due to the 65 spring or resilient action of the slide has a camming action on this inclined surface to shift the slide to the locked position. The parts are so proportioned that when the slide is shifted to the right to the fully released position the free end of the arm 69 rides up on to the substantially horizontal top edge of the tongue 59 and then retains this slide in the off or released position. It will thus be seen the operation is the same as in the other forms. The operating finger piece 75

70 projects through an elongated slot 71 in the cheek 72 for easy operation of the safety slide. The blade 58 is thrown out to the open position about its pivot 31 when it is released by means of 5 the spring 73 corresponding to the springs 8 and 33a of the other two forms.

It will be seen from the foregoing description that I have devised a construction which greatly increases the safety feature of the knife reducing 10 to a minimum the liability of the blade being inadvertently opened in the pocket or with ordinary handling, and furthermore that I have provided this improved safety feature without adding any additional parts to the knife but have merely 15 changed the shape or provided another tongue on parts already employed in this type of knife. Thus this improved safety feature adds none or very little extra to the cost of making the knife.

Having thus set forth the nature of my invention, what I claim is:

1. In a safety knife comprising a pivoted blade, a manually operable locking means for the blade and a shiftable means for holding said first means in locking position including a resilient element, 25 an inclined cam surface cooperating with said resilient element to shift the shiftable means to holding position.

2. In a safety push button knife including a pivoted blade, a locking lever for the blade, a push 30 button for operating the lever, a safety slide movable to and from a position to hold the lever in locking position and including a spring arm, manual means for shifting the slide, and an inclined cam surface cooperating with said spring arm 35 to shift the slide to holding position.

3. In a safety push button knife including a lining plate, a blade pivoted at one side of said plate, a locking lever for the blade pivoted to the plate, a push button for operating the lever, a 40 safety slide shiftable on the plate to and from a position holding the lever in locking position and including a spring arm, and manual means for shifting the slide, a tongue on the plate having an inclined cam surface cooperating with the 45 spring arm to shift the slide to holding position.

4. In a safety push button knife including a lining plate, a blade pivoted at one side of said plate, a locking lever for the blade pivoted to the plate, a push button for operating the lever, a 50 safety slide of resilient metal movable to and from a position to hold the lever in locking position, manual means for shifting the slide, and cooperating camming means on the slide and lining plate to shift the slide to holding position.

5. In a safety push button knife including a pivoted blade, a locking lever for the blade, a push button for operating the lever, a safety slide movable to and from a position to hold the lever in locking position and including a spring arm, manual means for shifting the slide, an inclined cam 55 cooperating with said spring arm to shift the slide to holding position, and said cam having a substantially flat surface at the top thereof onto

which said arm can slide to retain the slide in the released position.

6. In a safety push button knife including a lining plate, a blade pivoted at one side of said plate, a locking lever for the blade pivoted to the plate, a push button for operating the lever, a safety slide shiftable on the plate to and from a position holding the lever in locking position and including a spring arm, and manual means for shifting the slide, a tongue on the plate having an inclined cam surface cooperating with the spring arm to shift the slide to holding position, and said tongue having a surface at the top of the cam onto which the arm can rest to retain the slide in released position.

7. In a safety push button knife including a lining plate, a blade pivoted at one side of said plate, a locking lever for the blade pivoted to the plate, a push button for operating the lever, a safety slide shiftable on the plate to and from a position holding the lever in locking position, said slide including a top portion and a spring arm extending backwardly under the top portion, manual means for shifting the slide, and a tongue on the plate in alignment with the free end of the arm having an inclined surface cooperating with the free end of the arm to shift the slide to holding position.

8. The knife according to claim 7 in which the tongue has a surface at the top of the inclined surface onto which the free end of the tongue may slide to retain the slide in the released position.

9. In a safety push button knife including a lining plate, a blade pivoted at one side of said plate, a locking lever for the blade pivoted to the plate, a push button for operating the lever, a tongue struck up from the lining, a spring plate mounted on the lining by the tongue and extending under one end of the lever to hold it in locking position, a safety slide mounted on the lining and having an end portion movable to and from a position under the spring to hold the lever in locked position, manual means for shifting the slide, said slide including a spring arm extending under the slide, and a tongue struck up from the lining in alignment with the free end of the arm and having a cam surface cooperating therewith to shift the slide to holding position.

10. In a safety push button knife including a lining plate, a blade pivoted at one side of said plate, a locking lever for the blade pivoted to the plate, a push button for operating the lever, a tongue struck up from the lining, a spring plate mounted on the lining by the tongue and resting at its free end on the lever to hold it in locking position, a safety slide mounted on the lining and movable to and from a position under the lever to retain it in locking position, manual means for shifting the slide, said slide including a spring arm extending under the same, and said tongue having an inclined cam surface cooperating with said arm to shift the slide to holding position.

EDWARD J. CONKLIN.
